UNITED STATES PATENT OFFICE.

ALBERT ZOLLER, OF NEW YORK, N. Y.

FAUCET.

SPECIFICATION forming part of Letters Patent No. 243,340, dated June 21, 1881.

Application filed April 11, 1881. (No model.)

To all whom it may concern:

Be it known that I, ALBERT ZOLLER, a citizen of the United States, residing at New York, in the county and State of New York, 5 have invented new and useful Improvements in Faucets, of which the following is a specification.

This invention relates to that class of faucets for casks or barrels in which the nozzle 10 is provided with a lateral discharge-spout, and the stem of the valve operated by means of a screw-rod provided with a turning wheel or handle and arranged in the axis of the nozzle.

My invention consists, first, in the combination, in a faucet, of a hollow plug externally 15 screw-threaded, so as to screw directly into the cask or barrel, and provided at its outer end with a screw-threaded nipple, a cylindrical shell held against the end of the screw-threaded nipple by a coupling-ring engaging 20 said nipple and a flange upon the shell, a valve seating on a seat formed at the inner extremity of the screw-threaded plug, a screw-rod arranged to operate the valve-stem, and a discharge-spout leading from the shell; second, 25 in the combination, in a faucet, of the externally screw-threaded hollow plug which screws into the barrel, of a cylindrical shell provided with a discharge-spout and connected with the screw-threaded plug by a coupling-ring, 30 a valve seating on a seat formed at the inner extremity of the plug, the valve-stem passing through a guide in the hollow plug and provided with a head at its outer end, a spring arranged upon the valve-stem, between its head 35 and the said guide, the rod for operating the valve-stem passing a stuffing-box and provided with a screw-threaded portion arranged in an internally screw-threaded extension of 40 the cylindrical shell; third, in the combination, in a faucet, of the hollow plug with a tubular shell, provided at its outer end with two diverging spouts having stop-cocks, and also provided, between said discharge-spouts, with 45 an extension having a stuffing-box and a screw-threaded bearing for a screw-threaded rod, the valve arranged at the inner end of the plug, the valve-stem and spring, and the screw-rod for operating the valve-stem, all as hereinafter 50 more fully described.

This invention is illustrated in the accompanying drawings, in which Figure 1 represents a plan or top view. Fig. 2 is a longitudinal section.

Similar letters indicate corresponding parts. 55

In the drawings, the letter A designates a hollow plug, of brass or other suitable material, which is provided externally with a screw-thread, a, so that it can be screwed into and thereby firmly secured in the tap-hole of a cask 60 or barrel or other similar vessel. In the inner end of the plug is formed a beveled seat, a', for a cone-valve, B, the stem C of which extends through a guide, b, in the interior of the plug A. A spring, c, which surrounds the 65 valve-stem and acts upon a head d, secured thereto, has a tendency to hold the valve up to its seat. The webs p, which guide the valve in the hollow plug, are cut out as shown in Fig. 2, so as to allow a free passage for the 70 liquid when the valve is open.

D is a cylindrical or tubular shell, from which extend two discharge-spouts, E, which diverge from the shell D, as shown in Fig. 1, and each of them is provided with a stop-cock, so that 75 when one is used the other can be closed.

The shell D is provided at its inner end with an internally screw-threaded coupling-ring, o, adapted to engage with a screw-threaded nipple, d, that extends from the outer end 80 of the screw plug A, said coupling-ring being formed with an annular flange, O', that fits against a like flange, d', on the shell D, so that the shell will be held against the end of the said nipple, and thereby connected with the 85 hollow plug, and also so that it can be readily connected to or disconnected from the plug, in order to permit access to be had to the interior of the plug and shell, both for the purpose of cleaning out the same, and also for removing the spring in case of its becoming weakened or broken.

The shell D is provided at the crotch formed by the two diverging discharge-spouts E E with a tubular extension, E', the axis of which 95 is in line with that of the shell, and with that of the valve B and its stem C when the shell is secured to the plug A. In the outer end of this tubular extension is formed a stuffing-box, e, and in that part of said extension between 100

the shell D and the stuffing-box is formed an internal screw-thread, *f*, intended to engage with and constitute a bearing for a screw-rod, F, which is provided with a screw-thread, *f'*, and extends through the stuffing-box, and which is also provided with a hand-wheel, G, by means of which it can be screwed in or out. When the shell D is connected to the plug A the screw-rod F is in line with the valve-
10 stem C, and by turning said screw-rod inward the valve is opened and the liquid from the cask or barrel discharges freely through either one of the spouts E, according to which one of the stop-cocks *h* of said spouts is open. When the screw-rod F is turned back the valve closes and the liquid from the cask or barrel is prevented from passing into the plug A or shell D, while all, or nearly all, the liquid previously contained in said plug and shell discharges
15 through the open spout. In this way while drawing off the contents of the cask into bottles the discharge-spouts can be alternately employed, so that there will be no stop in the drawing off required.

20 What I claim is—

1. The combination, in a faucet, of the hollow plug A, externally screw-threaded, so as to screw directly into the cask or barrel, and provided at its outer end with a screw-threaded
25 nipple, *d*, the cylindrical shell D, held against the end of the screw-threaded nipple by a coupling-ring, O, engaging said nipple, and a flange upon the shell, the valve seating on a seat, *a'*, formed at the inner extremity of the screw-threaded plug, a screw-rod arranged to oper-

ate the valve-stem, and a discharge-spout leading from the shell, substantially as described.

2. The combination, with the externally screw-threaded plug A, of the cylindrical shell D, provided with a discharge-spout, and connected with said screw-threaded plug by the coupling-ring O, the valve B seating in a seat, *a'*, formed at the inner extremity of the plug, the valve-stem passing through a guide, *b*, and provided with a head at its outer end, the
40 spring arranged upon the valve-stem, between its head and the said guide, the rod F, for operating the valve-stem, passing through the stuffing-box *e* and provided with a screw-threaded portion, *f'*, working the internally
45 screw-threaded extension E of the shell D, substantially as described.

3. The combination, with the hollow plug A, of the shell D, provided at its outer end with the two diverging discharge-spouts having
50 stop-cocks, and also provided between said discharge-spouts with an extension, E', having the stuffing-box *e*, and a screw-threaded bearing for the screw-threaded rod F, the valve arranged at the inner end of the plug,
55 the valve-stem and spring, and the screw-rod for operating the valve-stem, substantially as described.

In testimony whereof I have hereunto set my hand and seal in the presence of two sub-
scribing witnesses.

ALBERT ZOLLER. [L. S.]
